FIG. 7

UNITED STATES PATENT OFFICE.

HARRY A. JOSELOWITZ, OF MINNEAPOLIS, MINNESOTA.

FOLDING BED.

Application filed June 1, 1925. Serial No. 34,043.

This invention relates to new and useful improvements in folding beds in general, and more particularly relates to such a device which may be folded into a relatively small 5 bundle for convenient handling in transit and storage, thereby adapting it for use by tourists and campers in that it may be conveniently packed away in a comparatively small space when traveling from place to 10 place.

The particular object of the invention is to provide an improved folding bed having the frame members so hinged and pivoted together that when the bed is folded, the 15 frame members will be in substantially parallel abutting relation, thereby providing such a structure which may be folded into a very small and compact bundle.

Other objects of the invention will appear 20 from the following description and the accompanying drawings and will be pointed out in the annexed claims.

In the accompanying drawings there has 25 been disclosed a structure designed to carry out the various objects of the invention but it is to be understood that the invention is not confined to the exact features shown as various changes may be made within the scope of the claims which follow.

30 In the accompanying drawings forming part of this specification:

Figure 1 is a perspective view of the improved bed in unfolded position;

Figure 2 is a plan view of Figure 1 showing 35 the structure partially folded;

Figure 3 is a similar view showing another step in the folding operation of the bed;

Figure 4 is a view showing the structure completely folded;

40 Figure 5 is an enlarged detail view in perspective showing the novel method of supporting the side frames of the bed upon the legs thereof;

Figure 6 is a similar view showing the legs 45 in folded position; and

Figure 7 is a detail view showing the novel construction of the joints provided in the side rail sections.

The novel folding bed featured in this 50 invention preferably comprises the opposed end rails 11 having the side rail sections 12 and 13 pivotally connected thereto as particularly shown in Figures 2, 3 and 4. The side rail sections 12 are pivotally connected 55 to the end rails 11 by means of suitable studs

or rivets 14 as shown in Figures 2, 5 and 6. The inner corners of the rail sections 12 are preferably rounded as shown at 15 so that they may be folded into the end rails 11 as shown in Figures 3 and 4.

60 A feature of the invention resides in the novel construction of the pivotal connection between the side rail sections 13 and the end rails 11. These connections are so constructed that when the bed is folded, the rail sections 13 will be spaced from the end rails 11, as particularly shown in Figure 4, thereby providing suitable clearance for the rail sections 12 which will be interposed between the rail sections 13 and the end rails 11 when

65 the frame is in folded position as shown in Figure 4. Referring to this figure, it will be noted that the side rail sections 13 each have a bracket 16 secured thereto which brackets have their opposite ends pivotally connected to the end rails 11 by pivot pins 17 located a short distance from the ends of the rails as

70 shown particularly in Figure 2. The pins 17 are located in the end rails 11 as above described so that when the bed is in folded position as shown in Figure 1, the outer faces of the rail sections 13 will be in alignment with the ends of the end rails 11, thereby providing a rectangular frame. The primary

75 object of the brackets 16 is to provide means for offsetting the rail sections 13 from the end rails 11 when the frame is completely folded for the purpose of providing clearance for the rail sections 12 which, as before mentioned, will be interposed between the end

80 rails 11 and the rail sections 13 when the structure is in the position shown in Figure 4.

85 Another feature of the invention resides in the novel construction of the pivotal connection between the side rail sections 12 and 13. Referring to Figure 7, it will be noted that the rail sections 12 and 13 are preferably constructed of angle bars and the rail sections 12 are preferably fitted over the sections

90 13. A shouldered stud 18 is secured to each rail section 12 to enter elongated openings or slots 19 provided in the adjacent end-portions of the rail sections 13 as shown. A

95 shouldered stud 21 is also mounted in the vertical web of each rail section 13 to enter bayonet slots 22 terminally provided in the adjacent end-portions of the rail sections 12. By this novel construction, it will be noted

100 that the rail sections are also adapted for a

105 110

longitudinal or slidable movement to provide for securely locking the sections together when the bed is in unfolded position as shown in Figure 1.

5 In the operation of this novel hinge construction the pivot pins 21, when the bed is in unfolded position, will be seated in the recesses 23 of the sockets 22, thereby preventing the rail sections from accidentally pulling apart or becoming unlocked so that they 10 may be folded as shown in Figures 2 and 3. When it is desired to fold the bed, a slight upward movement is imparted to the pivotal connection of the rail sections 12 and 13 15 which will cause the pivot pins 21 to be moved downwardly out of the recesses 23 in the rail sections 12, after which the sections may be pulled apart as shown in Figure 7. When the pivot pins 21 mounted in the sections 13 have 20 thus been removed from the bayonet slots 22, the two sections on each side of the bed may readily be folded as shown in Figures 2 and 3. When the bed is erected, as shown in Figure 1, and the pivot pin 21 are again seated in the 25 recesses 23, of the slots 22, the side rail sections will be securely held together substantially as a one-piece structure, thereby providing a very substantial pivotal connection between the rail sections so that such connections cannot accidentally become unlocked 30 from each other.

The arrangement of the end irons with their concave faces directed inwardly and downwardly, and with the side rails pivoted 35 beneath the end rails, disposes the upper portions of the vertical flanges of the end rails as abutments for the end faces of the side rails, to receive the thrust caused by the tension of the spring fabric 24.

40 The extensions 16 are principally for the purpose of permitting nesting in the manner shown in Figure 4, wherein it will be seen that the arm 16 acts to dispose the rails 13 outwardly so that all members of the device can 45 assume a strictly parallel relation when nested.

Another feature of this invention resides in the novel method of pivotally connecting the supporting legs 24 to the end rails 11. 50 Referring to Figure 5, it will be noted that each leg 24 is also constructed of angle bar and that the upper portion of one of the webs thereof is cut away to provide a lug or extension 25 which is pivotally connected 55 to the end rail 11 by means of a pin 26. Suitable braces 27 are pivotally connected to the leg and have their upper ends adapted to be demountably connected to the pins 28 and 29 in the end rail 11 and rail section 12, respectively, as shown. When the leg is in unfolded position as shown in Figure 5, the diagonal braces 27 are secured to the pins 28 and 29, thereby securely bracing the leg in unfolded position. A feature of the construction above described resides in the par-

ticular location of the pivot pin 26 in the end rail 11, which preferably is such as to cause the upper end 31 of the relatively shorter web of the leg to abut against the lower edge 32 of the side rail section 12, when the leg is in 70 unfolded position. By this novel arrangement, it will readily be understood that when the bed is set up, as shown in Figure 1, the weight of the rail sections 12 and 13 and the load carried thereby will not be carried entirely by the pivot pins 26, but rather upon the upper ends of the legs 24 as a result of the lower edges 32 of the rail sections 12 and 13 bearing directly against the upper ends 31 of the legs as clearly shown in Figure 5. 75 When it is desired to fold the bed to the position shown in Figure 4, the diagonal braces 27 will be disconnected from the headed pins 28 and 29 after which the legs may readily be folded against the end rails 11 as shown in 80 Figure 6.

An offset plate 33, having a plurality of spaced apertures 34, is suitably secured to each end rail 11 to provide means for securing thereto and usual fabric covering 34 shown 90 in Figure 1. This covering may be of any suitable material applicable for the purpose, and as it forms no part of the present invention, it is thought unnecessary to show same in detail.

In the operation of folding this novel bed the legs 24 are first folded to the position shown in Figure 6, and the rectangular bed frame placed upon the floor. The pivotal connections in the side rail sections 12 and 13 are then unlocked by slightly raising each joint so as to cause the rail sections 13 to be 95 downwardly moved to the dotted line position shown in Figure 7, after which the pins 21 may be moved out of the recesses 23 and the rail sections pulled apart as shown in this figure. The rail sections 12 and 13 are then inwardly folded as shown in Figure 2, the rail sections 12 following the paths indicated by the dotted lines and arrows in Figure 2. Continued inward movement of the rail sections 100 will cause the end rails 11 to be inwardly drawn to the position shown in Figure 3 after which the entire bed may be folded into the position shown in Figure 4, wherein 105 it will be noted that the rail sections, end rails, and the legs 24 will be substantially in parallel relation and in such a manner that the folded bed as a whole may be stored or packed away in a relatively small space.

110 This novel structure is also preferably constructed of angle iron bars thereby providing a folding bed which, when in unfolded position as shown in Figure 1, will provide a very rugged and substantial bed capable of carrying a considerable weight without danger of collapsing. Also as a result of the means provided for locking the pivotal connections of the rail sections 12 and 13 in unfolded position, the bed as a whole, may readily be 115 120 125 130

moved about upon the floor without danger of accidentally collapsing or folding together.

I claim as my invention:

- 5 1. A folding bed frame formed from angle-iron material including a pair of end rails having their concave sides facing inwardly and downwardly, and side rail members pivotally connected to said end rails with their
- 10 concave sides facing outwardly and downwardly, each side rail member composed of two sections nested and overlapped at their inner ends and pivotally connected together, one section of each side rail having a right
- 15 angular terminal extension terminally pivoted beneath respective end rails.
- 20 2. A folding bed frame formed from angle-iron material and including a pair of end rails having their concave sides facing inwardly and downwardly, and side rail members pivotally connected to the end rails with their concave sides facing outwardly and downwardly, each side rail being composed of two
- 25 sections overlapped, nested and pivotally and slidably connected, for locking them in alined position, one section of each side rail having a right angular terminal extension terminally pivoted beneath the top flanges of respective end rails.
- 30 3. A folding bed frame formed from angle-iron material and comprising end rails having their concave sides facing inwardly, and side rails having their concave sides facing outwardly, each side rail comprising two sec-
- 35 tions having their inner ends overlapped, nested and pivoted together at a point inwardly from their ends, to limit outward movement in alined relation, one section of each side rail having a short right angular
- 40 terminal extension terminally pivoted, terminally of and beneath respective end rails,

at points diagonally of the frame, and the other sections being directly terminally pivoted terminally of said end rails, all sections being of substantially less length than the 45 end rails, and adapted by swinging inwardly, to nest beneath the end rails, with the non-angled sections above and between the pivotal points of the side rails with the end rails, and with the angled sections on the bot- 50 tom of the nested pile of elements.

4. A folding bed frame formed from angle-iron material, comprising end rails having their concave sides facing inwardly, and side rails having their concave sides facing out- 55 wardly, each side rail comprising two sections having their inner ends overlapped, nested and pivoted together at a point inwardly from their ends, to limit outward movement in alined relation, one section of 60 each side rail having a short right angular terminal extension terminally pivoted, terminally of and beneath respective end rails, at points diagonally of the frame, and the other sections being directly terminally pivoted terminally thereof, all sections being of substantially less length than the end rails, and adapted by swinging inwardly to nest beneath the end rails, with the non-angled sections above and between the pivotal points 65 of the side rails with the end rails, and with the angled sections on the bottom of the nested pile of elements, and legs pivoted to and adapted to swing inwardly beneath and at opposite ends of the end rails to engage 70 beneath the nested side rails to enclose the same, said legs adapted to abuttingly engage beneath and terminally of the side rails as a stop, when in set-up position.

In witness whereof, I have hereunto set 80 my hand this 26th day of May, 1925.

HARRY A. JOSELOWITZ.
